UNITED STATES PATENT OFFICE.

JULIUS LERCHE, OF STEGLITZ, NEAR BERLIN, GERMANY, ASSIGNOR TO DEUTSCHE POST- UND EISENBAHN- VERKEHRSWESEN AKTIENGESELLSCHAFT (DAPAG-EFUBAG), OF STAAKEN, NEAR SPANDAU, GERMANY.

DEVICE FOR PRINTING PREPAID POSTAGE ON POSTAL PACKAGES.

1,089,928.

Specification of Letters Patent. Patented Mar. 10, 1914.

Application filed January 24, 1912. Serial No. 673,248.

To all whom it may concern:

Be it known that I, JULIUS LERCHE, Royal Councillor of Construction, a subject of the German Emperor, and residing at 14 Arndtstrasse, Steglitz, near Berlin, Prussia, Germany, have invented new and useful Improvements in Devices for Printing Prepaid Postage on Postal Packages, of which the following is a specification.

10 This invention relates to an apparatus for printing upon letters and postal packages, stamps or other indications of prepaid postage, the object of the invention being to provide a device that will serve as a substitute for the slow and laborious work of gumming adhesive stamps to mail matter by those who send out large quantities of mail every day.

The invention comprises a closed casing 20 through which a passageway is formed for the matter to be stamped. Within the casing is a revoluble shaft, hand or power driven, on which are a plurality of printing rollers projecting into said passageway, each 25 roller provided with a stamp differing in value from those of the other rollers for printing the prepaid amount on the letter or package as it travels through the passageway, the stamps being printed in different 30 colors according to their different values. The printing rollers are loose on the shaft but may be moved longitudinally thereon to bring one or two of them as desired into proper relation to the passageway and into 35 engagement with a fixed key on the shaft and be rotated thereby to print one or two stamps on a letter or package within the passageway.

A separate registering device or counter 40 for each printing roller is provided and brought into operative connection therewith when said roller is moved into printing position. Means are also provided for locking against rotation, such printing rollers as 45 are not in engagement with the shaft by means of said key. There is also provided efficient means for locking in fixed position each counting mechanism or register and releasing the same coincident with locking 50 and unlocking its respective printing roller.

Counter pressure rollers are provided for holding the matter to be stamped close against the printing rollers, and to maintain said counter pressure rollers always in

proper relation with the printing rollers as 55 the latter are moved longitudinally on the main shaft, suitable adjusting mechanism, operated simultaneously with the change of position of the printing rollers is provided for this purpose. 60

To more clearly set forth the features of the invention above enumerated, and others to be described, attention is directed to the accompanying drawings forming a part of this specification in which— 65

Figure 1 is a vertical longitudinal sectional view of the preferred form of the invention. Figs. 2 and 3 are detail views of feeding means which may be applied when the passage of a letter through the apparatus is to be retarded for printing stamps thereon in succession. Fig. 4 is a cross sectional detail view of means for locking the printing rollers against rotation, and for controlling the position of the counter pressure rollers. Fig. 5 is a sectional view similar to Fig. 1 of a modified form of the invention. Fig. 6 is a cross sectional view through the apparatus illustrated in Fig. 1. Figs. 7 and 8 show detail views of certain adjusting 70 mechanism for the counter pressure rollers of the apparatus illustrated in Fig. 9. Fig. 9 is a vertical longitudinal sectional view of a further modification. Figs. 10 and 11 are views illustrating other modifications. 75

In the drawings, 5 indicates the main driving shaft extending longitudinally through the casing A of the apparatus which may be turned by hand or power for imparting rotary movement to the printing 80 rollers and other mechanism by means hereinafter described. Mounted loosely on the shaft 5 about midway its length are four printing rollers 1, 2, 3 and 4 spaced apart a suitable distance and contained within a 85 support or cage 8, through a slot 6 in one side of which said rollers project into a passageway 7 for the articles to be stamped. On each roller 1, 2, 3, and 4 is a stamp printing block or die, said dies differing in value and here shown as 10, 20, 5 and 3 pfennig stamps respectively. Projecting upwardly from the center of the cage 8 and surrounding the shaft 5 is a hollow stem 10, its upper end passing through the casing A and having thereon an exterior screw thread 10' engaging a thread on the interior of a sleeve nut 15 inclosing said stem. A shoulder 16

on the sleeve nut 15 engages a groove in a collar 43 threaded in a boss 44 on the casing A, so that on rotating the sleeve nut 15, the stem 10 with the cage 8 and printing rollers will be raised and lowered. The purpose of the threaded collar 43 will be described later.

Secured to the shaft 5 is a key 9 adapted to engage a keyway in any one or an adjacent pair of said printing rollers as they are raised or lowered and, rotate it or them, such rollers as are not connected with the shaft being held against rotation by a blade 29 fixed on the casing A and projecting into peripheral grooves 1^a, 2^a, 3^a and 4^a in the respective printing rollers. A notch 29^a is cut in the blade 29 in line with the key 9 sufficiently wide for the passage of two rollers so that when two rollers are connected 20 to the shaft by the key they will be disengaged from the blade and free to rotate.

Slidable longitudinally on the main shaft 5 below the cage 8 and rotatably connected to the shaft by a long key 14, is a gear wheel 13 mounted in a collar bearing 12 on an arm 11 projecting downwardly from the cage 8, by which means the gear wheel is moved vertically coincidentally with the cage and the printing rollers. Disposed around the gear wheel 13 are four gear wheels 17, 18, 19 and 20, each fixed on a separate shaft 17^a, 18^a, 19^a and 20^a at different elevations so that as the gear wheel is raised and lowered on its shaft 5 it will engage one or two of said surrounding gear wheels and rotate it or them. The widths of the several gear wheels is such that whenever the key 9 is in engagement with one only of the printing rollers, the gear wheel 13 is in engagement 40 with but one of the other gear wheels 17-20, but when said key secures two of said printing rollers to the shaft 5, the gear wheel 13 is in mesh with two of the gear wheels 17-20. On each shaft 17^a, 18^a, 19^a and 20^a 45 is a pinion 21 said pinions engaging gear wheels 22, each forming a part of a separate counting device 24 having number wheels 23, 25 and 26.

The gear wheels 17-20 are prevented 50 from rotating when disengaged from the gear wheel 13, and the counting devices connected thereto held against movement by a locking device comprising a cylinder 27 fast on each shaft 17^a, 18^a, 19^a and 20^a, each cylinder being formed with two parallel circumferential grooves 27^a, 27^b and a longitudinal groove 27^c with which latter grooves engage fingers 28 projecting from the cage 8 to normally hold said cylinders from turning, but whenever one of said fingers is in line with either circumferential groove of its co-operating cylinder, the latter can be rotated and its connected register operated.

The circumferential grooves 27^a, 27^b of each cylinder 27 are spaced apart a distance

between centers, equal to one half the distance between the centers of the printing rollers and lie in different planes, the upper grooves 27^a of one cylinder being in the same plane as the lower groove 27^b of the cylinder next adjacent on one side while its lower groove 27^b lies in the same plane as the upper groove 27^a of the cylinder next adjacent on the other side. The fingers 28 in this arrangement of the grooves will all be in the same plane.

As illustrated in Fig. 1, the printing roller 4 containing the 3 pfennig stamp block is connected by key 9 to shaft 5 and being in alignment with the notch 29^a in the blade 29, it will rotate when the shaft is turned. The gear wheel 13 is in engagement with the gear wheel 20 of the counter 24 for registering 3 pfennig stamp which is free to operate as the finger 28 lies in the circumferential groove 27^a of cylinder 27 on the shaft of gear wheel 20. If mail matter be fed into the passageway 7 and the shaft 5 rotated, each will have a 3 pfennig stamp printed thereon.

If it be desired to print 5 pfennig stamps, the sleeve nut 15 is turned which through its connection with the thread 10^a on the stem 10 lowers the cage 8 and the printing rollers until the roller 3 is in the place now occupied by the roller 4. This position is shown by means of an indicator 50 on the upper end of the sleeve 10 which may be, as shown, in the form of a ring having a colored or otherwise distinctively marked surface visible through openings 51 in opposite sides of the sleeve nut 15. These openings on one side and in line with one another show the indicator through one of them when a single printing roller is in position to print, but when the indicator is visible through an opening on the opposite side of the sleeve nut, then two printing rollers are in place. Lowering the cage 8 to the position described disconnects the printing roller 4 from the key 9 and engages it with the blade 29 below the notch 29^a, and at the same time moves the gear wheel 13 into engagement with gear wheel 19 on shaft 19^a of the 5 pfennig counter. The fingers 28 move down in the longitudinal slots 27^c in the cylinders 27 to such an extent that the one in the slot in the cylinder on shaft 20^a descends below the circular groove 27^b and locks the 3 pfennig counter, while the finger engaging the cylinder on shaft 19^a stops in line with the groove 27^a of said cylinder so that the 5 pfennig counter may operate. To print 25 pfennig postage on a letter, the cage 8 is again lowered one half the distance between two printing rollers, or until the indicator 50 is visible through the uppermost opening on the opposite side of the sleeve nut 15. This brings printing rollers 3 and 4 both into engagement with the key 9 and in alignment with the notch 29^a in the blade 29.

ment with notch 29^a, the gear wheel 13 will bridge the space between gear wheels 19 and 18, and mesh with both of them for operating the 5 and 20 pfennig counters, while fingers 28 engaging the cylinders 27 on shafts 19^a and 18^a will align with groove 27^b of the former cylinder, and groove 27^a of the latter cylinder. Further lowering of the cage 8 will enable an operator to print postal rates of the values of 20 and 10 pfennig each by a single printing roller, and of 30 pfennig by means of these two rollers combined.

It is sometimes necessary or desirable to print a stamp on a letter at a different distance from the edge thereof than usual, as for instance when, after one stamp has been printed, a second is to be applied above or below the first one. This may be done by means of the collar 43, which on being rotated in one or the other directions, turns in the threaded boss 44 on the casing A and rises or descends carrying the sleeve nut 15 with it, which through the loose connection 16 moves up and down without rotation. The cage 8 with the printing rollers 1, 2, 3 and 4, the fingers 28 and the gear wheel 13 is by this movement of the sleeve nut raised and lowered. To prevent false counting on the registers 24 under these conditions, the gear wheels 17-20 and the locking cylinders 27 must move in unison with the printing rollers. For this purpose, the collar 43 has a disk 46 fixed on its lower end and also a gear wheel 47, the use of which gear will be described later. Between the disk 46 and the gear wheel is a hub projecting from one of them rotatable in a plate 45 in which also turn the upper ends of the shafts 17^a-20^a, held against endwise movement therein by collars 48 on each shaft above and below the plate. When the collar 43 is turned to raise and lower the cage 8 and connected parts, the plate 45 is carried with it as also are the shafts 17^a-20^a with their cylinders 27, pinions 21 and gear wheels 17-20. The position of these various parts shifted by the collar 43 is indicated by means of a spring finger 49 provided with a vertical scale, and which bears against the collar, as shown in Fig. 1.

It will be evident that the relative position of the gear wheel 13 with respect to the gear wheels 17-20 will remain undisturbed, and that changing the position of the printing rollers will not interfere with the correct operation of the counters. The pinions 21 on the shafts 17^a-20^a are quite wide, as shown, to keep them in engagement with the gear wheels 22 of the counting mechanisms in all positions of said shafts.

Letters and other matter to be stamped are held against the printing rollers by means of counter-pressure rollers 88, 89 journaled respectively in yokes 92, 93 pivoted on

a vertical shaft 90 within a housing 91, which yokes can also oscillate about the axis of the shaft 90. Brackets 62, 63 project from the side of the casing A in which the ends of the shaft 90 turn and also slide longitudinally.

The housing 91 is carried on a vertical shaft 94 that has a sliding bearing in the bottom of casing A, and a similar bearing in a threaded sleeve 98 in the top of the casing, the shaft turning in said housing, but is prevented from moving endwise relatively thereto by means of collars 95, 96 fixed on the shaft on opposite sides of one of the frame plate forming the housing. As constructed, any longitudinal movement imparted to shaft 94 will carry the housing in the same direction as also the shaft 90 and the counter pressure rollers and their supporting yokes.

The threaded sleeve 98 has fixed thereon, between its ends, a gear wheel 97 meshing with the gear wheel 47 on the collar 43, while its lower end has a swiveled connection 99 with the closed upper end of a cylinder drum 100 through the center of which passes the shaft 94 connected to the drum in such manner as to turn therewith but permitting the drum to slide longitudinally thereon. Fixed on the upper end of the drum 100 is a gear wheel 101 in engagement with a smaller gear wheel 102 keyed on the lower end of the sleeve nut 15. From this it will be apparent that when the sleeve nut 15 is rotated to raise and lower the hollow stem 10, the gear wheel 102 will turn the gear wheel 101 and with it the drum 100 and shaft 94. Because of the swiveled connection 99 the sleeve 98 will not turn. On turning the collar 43, the gear wheel 47 thereon through its connection with the gear wheel 97 revolves the sleeve 98, thus causing it to move up and down in its threaded bearing in the casing A. The drum 100 and the shaft 94 are also raised and lowered with the sleeve 98, but they do not rotate. The shaft is moved longitudinally with the drum by means now to be described.

Within the drum 100 is a cylinder 105, loosely mounted on the shaft 94, but prevented from sliding thereon by collars 107, 108 fixed on the shaft above and below the cylinder. Around the periphery of the cylinder is formed a cam groove 105^a, curved as shown, into which project two pins 103, 104 from diametrically opposite sides of the drum. By means of these pins, when the drum is raised and lowered through the turning of the sleeve 98, the cylinder 105, and of course the shaft 94 move with it. Furthermore, when the drum is rotated by the gear wheels 102, 101, the pins 103, 104 turning in a horizontal plane and riding in the cam groove 105^a, move the cylinder and shaft up and down a distance regulated by

the throw of the cam groove. The cylinder 105 is prevented from turning by means of a fixed pin 106, parallel to the shaft 94, that passes freely through a hole in the cylinder.

With the parts arranged as described, let the ratio of the gear wheels 101 and 102 be two to one; the pitch of the thread on the sleeve nut 15 such that one complete rotation thereof will raise or lower the printing rollers a distance equal to that between centers of two printing rollers, and the throw of the cam groove 105^a be the same as the distance between said rollers. Then, after each one half revolution of the sleeve nut 15 to bring one or the other printing roller 1-4, or two of them into printing position, the drum 100 will be turned one quarter of a revolution and the pins 103, 104 traveling in the cam groove will move the counter pressure rollers 88, 89 a distance equal to that of the printing rollers and will thus always keep in proper alignment with them.

If the stamps are to be printed from two of the printing rollers, both pressure rollers remain in operative position, but if one stamp only is to be printed, the counter pressure roller not required will be withdrawn from the passage way 7 by means hereinafter described.

Fixed on the main shaft 5 below the cage 8 is a disk 82, the periphery of which is formed with a radial notch 83 which the hooked end 84 of a hand lever 75 may engage and lock the shaft against rotation. The lever 75 has a hub 113 mounted on the shaft 90 and secured against rotation thereon by a key or other suitable means, which will permit the shaft to slide in said hub. A swiveled or other connection with the bracket 63 permits the hub to turn with the shaft 90 but prevents it moving in the line of the shaft. A lug 114 is carried by the hand lever 75 to engage one of a series of peripheral notches 115^a in a broad disk 115 on shaft 94 when it becomes necessary to lock said shaft from turning. In the form of apparatus shown the disk 115 is provided with four notches 115^a ninety degrees apart.

The yoke 92 supporting the counter pressure roller 88, is keyed on the shaft 90 to turn therewith when the hand lever 75 is operated. The yoke 93 is mounted on a sleeve 109 that turns freely on the shaft 90. Projecting from the yoke 92 or the hub thereof is an arm 112 connected to a spring for normally holding counter pressure roller 88 in the passage way 7 and the hand lever in the position shown in Fig. 4 with the lug 114 in engagement with one of the notches in the disk 115, and the hooked end 84 withdrawn from the notch in disk 82. Shaft 5 is thus free to rotate while shaft 94 is locked in position. From yoke 93 or its hub project two arms 110 and 111 in

substantially opposite directions, arm 110 being directed toward and above the disk 115 and arm 111 in about the same direction as arm 112. A spring connected to the arm 111 tends to hold the counter pressure roller 88 in the passageway 7. A pin or stud 116 projects up from the disk 115 in position to engage the arm 110 on the yoke 93 and when in the position shown in Fig. 4, hold the counter pressure roller 88 carried by said yoke away from the printing rollers against the tension of the spring attached to arm 111. The spring connected to arm 112 however is unrestrained, therefore the roller 88 is in operative position in the passage way 7 and the hand lever 75 in position to lock the shaft 94 through the lug 114 engaging a notch 115^a, and unlock the main or printing roller shaft 5 by the withdrawal of the hooked end 84 from the notched disk 82.

If now the printing rollers be moved into their normal position so that the notched disk 82 will engage the hooked end 84 of the hand lever 75, then on moving the hand lever in the direction of the arrow, Fig. 4, shaft 5 will be locked and shaft 94 released. The shaft 90, turning with the hand lever swings the yoke 92 and counter pressure roller 88 away from the printing roller, carrying the arm 110 into the position indicated by dotted lines, and the arm 112 against arm 111 to further withdraw counter pressure roller 88. With the parts in position described, the sleeve nut 15 on being turned, rotates the gear wheels 102, 101, drum 100, and the pins 103, 104 traveling in the cam groove 105^a, will move the cage 8 and rollers 88, 89 to the desired position. It is to be remembered that the sleeve nut must be turned a full half revolution or multiple thereof otherwise one of the notches 115^a will not be in position to be entered by the lug 114 on the hand lever when moved to lock shaft 94 and disengage the main shaft 5 and the printing rollers thereon.

If stamps are to be printed at a given distance apart in the direction of the feed through the apparatus, the arrangement shown in Figs. 2 and 3 may be employed. As there shown 116^a and 117 indicate two feed rollers for the matter to be stamped, running substantially in contact with one another and turned in the same direction, so that their opposed edges will move in opposite directions as indicated by the arrows. By this arrangement letters introduced between the rollers will not be advanced because the surfaces of the said rollers move in opposite directions. But, as soon as a soft pad 118 on the roller 116 traveling in the direction of the feed bears upon the letter, the increased friction of said pad will overcome the resistance offered by the oppositely moving roller 117 and advance the

letter in the passage way 7. As this advance will of course sooner or later depend upon the relative position of the soft pad to the roll 117 the position of the stamp on the letter may be adjusted by turning the feed roller 116^a on a drive spindle 119.

For regulating the adjustment of said feed roller a disk 120 is fitted on the spindle 119 over a polygonal shoulder thereon to prevent its rotation and held in place by a thumb nut 122 which presses said disk against the roller for the purpose of fixing it firmly on said spindle. On the face of the disk is an index line 121 while graduations are made on the adjacent face of the roller 116^a for the purpose of setting the same that letters fed through the machine may be fed in proper position.

For the purpose of keeping the passage way closed as far as possible, shields 123, Figs. 1 and 9, are provided on the cage, which shields cover the slot 6 for the printing rollers and counter pressure rollers as soon as said rollers have been removed therefrom. In addition to the shields a thin metal sheet 124 is used to cover the opening if the shields 123 are permitted to enter too far into the passage way. A ratchet wheel 125, on the shaft 5, and a pawl 126 to engage the same are used to prevent reverse rotation of the main shaft 5. Besides the feed rollers 116^a and 117 for advancing matter, other rollers 129, 130, 131 and 132 are journaled within the passage way 7 to insure the complete passage of material through the apparatus.

Projecting laterally from one side of the cage are a series of inking fountains 39, one for each printing roller and spaced from one another by horizontal partition 38. Within the several fountains are rollers 30, 31, 32 and 33 for applying ink to the printing rollers, while inking rollers 34, 35, 36 and 37 keep the applying rollers supplied with ink. These fountains being separated by the partitions 38, are each supplied with ink of a different color so that the different stamps when printed will have a different color value as well as numerical value. A door 40 in the side of the casing permits ready access to the fountain.

If desired the blade 29, for preventing unnecessary rotation of the printing rollers, may be made vertically adjustable, as shown in Fig. 9. In said figure, 29^a designates the blade which extends from the bottom of the casing A to the top thereof, and slidably in bearings formed thereon, said blade passing through the vertically adjustable plate 45 which raises and lowers the shafts 17^a, 20^a, and is held in said plate by collars, one placed above and below the plate as shown. This same figure also shows a modification of the locking means for the said shafts 17^a—20^a, which comprises a disk 27^a secured

to each shaft adapted to enter one of two notches in a vertical bar 28^a, when the shaft is to rotate, fixed to the cage 8. At other times the bar enters a notch in the disk and prevents it turning.

Fig. 5, shows a modification of a means for adjusting the position of the stamp on the letter with respect to its upper edge. As here shown the bottom 41 of the passage way 7 is made separate from the rest of the casing and is secured in place by means of a thumb nut 42, movable in a vertical slot in the side of the casing A, so that on loosening the nut the position of the bottom of the passage way may be changed to suit the position on the letter where it is desired to place the stamp.

If it be desired to use a separate counter pressure roller for each printing roller this may be done by the modification shown in Figs. 7 and 8. Here the counter pressure rollers 55, 56, 57 and 58 are each mounted on a separate horizontal swinging lever 53, against each of which bears a spring 53^a to hold the counter pressure rollers in contact with the printing rollers. If, however, it is desirable that the counter pressure rollers which are not in operation be held out of contact with the printing rollers, a vertical blade 54 is provided against which the forwardly projecting ends 52 of the swinging arms 53 bear, and hold the counter pressure rollers out of the passage way 7. To permit one of these rollers, or two if necessary, to move into position when stamps are to be printed, a notch 54^a is made in the side of the blade 54 whereby the swinging arms 53, under the influence of the spring 53^a, may swing toward the printing roller. The upper and lower edges of the notch 54^a are inclined to permit the ends of the swinging arms entering and leaving the same with as little friction and interruption as possible.

Fig. 9 shows the blade 54 mounted similar to that of 29^a so that it may move vertically with the cage, and instead of forming a notch 54^a in the side of the blade with beveled ends, a series of rectangular notches 59, 60 and 61 are provided for the ends 52 of the swinging arms 53. Another modification for moving the counter pressure rollers to and from the printing rollers is illustrated in Figs. 10 and 11. As shown the counter pressure rollers 55—58 are each carried in one of the swinging arms 66, 67, 68 and 69, swinging freely on the vertical shaft 90 and each acted on by a spring 65 to hold the counter pressure rollers against the printing rollers. Projecting upwardly from each swinging arm near the shaft 90 are two pins 72 and 73 which are adapted to be engaged by a pin 71 which passes through the shaft 90. When the hand lever 75 is moved into position to lock the main shaft 5 the shaft 90 on which said lever

is mounted is turned, and the pin 71 carried thereby after a certain amount of free movement engages the pins 72 and 73 and swings the counter pressure rollers away from the printing rollers. Each swinging arm 66-69 has a finger 80 which bears against the blade 54 and holds the counter pressure rollers away from the printing rollers, except when such finger is opposite one of the rectangular notches 59, 60, 61 in said blade. When in said position the finger enters the notch and the counter pressure roller bears against the printing roller. To prevent the cage 8 being moved a rack 81 is provided in suitable position, with which the hand lever 75 will engage when moved to unlock the main shaft 5.

76 indicates a door leading into the housing for the counter pressure rollers pivoted at 77 and having an outwardly standing lug 78 in position to be engaged by the hand lever 75 when the latter is locked to the rack 81. In this position when the printing rollers are free to turn and be more or less exposed, it is impossible to open the door 78 without moving the lever 75 which cannot be done if the notch 83 in the locking disk 82 is out of line with the hook end 84 of the lever 75. When this notch is in line with the hook end then the lever 75 may be swung away from the door and the latter opened but at this time the stamp die on the printing roller will have been moved to a position within the casing and away from all danger of tampering or interfering therewith. A simple arrangement for mounting the counter pressure rollers is shown in Fig. 5, and is advantageous when the bottom of the passage way 7 is made adjustable as there shown. In this instance three counter pressure rollers 85, 86 and 87 are employed. The middle roller 86 of the three, is sufficiently wide to extend from the middle of one printing roller to the middle of the adjacent printing roller. The end counter pressure rollers however, are only half as wide. These rollers are mounted on a spindle 88^a having squared ends 88^b carried in oscillating levers 89^a pivoted to the housing surrounding the rollers 85, 86 and 87 in a manner well understood to permit said rollers swinging to and from the printing rollers. The spindle 88^a is of one diameter around which the roller 86 turns, beyond which its ends are reduced or of less diameter and eccentrically arranged with respect to the central portion. The disks 85-87 are mounted to turn on hubs projecting from a handle 91^a through which hubs the smaller portions 88^c of the shaft pass. By means of this handle 91^a these disks may be rotated about the reduced portion 88^c of the shaft 88^a. In the position shown all three rollers offer pressure against the lower printing rollers 3 and 4, but if the

handle be swung about more or less the eccentricity of the shaft ends 88^c will cause the pressure rollers 85-87 to be moved out of line with the roller 86 and away from the print rollers.

70 What is claimed is:

1. In an apparatus of the character described, a rotatable shaft, a plurality of stamp printing rollers mounted to rotate and move longitudinally on said shaft, means for rotatably connecting one or an adjacent pair of rollers to said shaft, means for moving said rollers longitudinally on the shaft, means for locking the remainder of the rollers against rotation, and an independent mechanism for registering the imprint of each printing roller.

2. In an apparatus of the character described, a rotatable shaft, a plurality of stamp printing rollers mounted on said shaft and adapted to rotate and to move longitudinally thereon into printing position, means for rotatably connecting one or an adjacent pair of rollers to said shaft, counterpressure rollers for coöperating with the printing rollers, an independent mechanism for registering the imprint of each printing roller, and means controlled by the longitudinal travel of said rollers for connecting only to the roller in printing position its individual registering mechanism and disconnecting the remainder.

3. In an apparatus of the character described, a rotatable shaft, a plurality of stamp printing rollers mounted on said shaft and adapted to rotate and to move longitudinally thereon into printing position, means for rotatably connecting one or an adjacent pair of rollers to said shaft, counterpressure rollers for coöperating with the printing rollers, an independent mechanism for registering the imprint of each printing roller, means controlled by the longitudinal travel of said rollers for connecting only to the roller in printing position its independent registering mechanism and disconnecting the remainder, means for locking against rotation all printing rollers not in use, and means for locking against false rotation the inactive registering mechanisms.

4. In an apparatus of the character described, a rotatable shaft, a plurality of stamp printing rollers mounted to rotate and move longitudinally on said shaft, means for rotatably connecting one or an adjacent pair of rollers to said shaft, means for imparting longitudinal movement to said rollers to cause their engagement with the shaft, counter pressure rollers to co-operate with the printing rollers, and means for moving said counter pressure rollers in an end-wise direction coincident with the longitudinal movement of the printing rollers.

5. In an apparatus of the character described, a rotatable shaft, a plurality of stamp printing rollers mounted to rotate and move longitudinally on said shaft, means for rotatably connecting one or an adjacent pair of rollers to said shaft, counter pressure rollers to coöperate with the printing rollers, rotating means for moving said printing rollers longitudinally on the shaft, 10 and similar means for moving in unison the counter pressure rollers and operated by the moving means of the printing rollers.
6. In an apparatus of the character described, a rotatable shaft, a plurality of 15 stamp printing rollers mounted to rotate and move longitudinally on said shaft, means for rotatably connecting one or an adjacent pair of rollers to said shaft, counterpressure rollers for coöoperating with the 20 printing rollers, a cage in which said printing rollers are carried, a hollow stem attached to said cage and surrounding said shaft, and a threaded member on said hollow stem which on being rotated moves the 25 printing rollers longitudinally.
7. In an apparatus of the character described, a rotatable shaft, a plurality of stamp printing rollers mounted to rotate and move longitudinally on said shaft, 30 means for rotatably connecting one or an adjacent pair of rollers to said shaft, counterpressure rollers for coöoperating with the printing rollers, a cage supporting said printing rollers, a hollow stem projecting 35 from one side of said cage and having a thread on its outer end, a sleeve nut threaded on said hollow stem for longitudinally moving the printing rollers, and a collar 40 threaded in the casing of the apparatus in which said sleeve nut is swiveled which on being rotated moves said sleeve nut in a longitudinal direction.
8. In an apparatus of the character described, a rotatable shaft, a plurality of 45 stamp printing rollers mounted to rotate and move longitudinally on said shaft, means for rotatably connecting one or an adjacent pair of rollers to said shaft, a cage in which said printing rollers are supported 50 having a hollow stem projecting therefrom in which said shaft rotates, a sleeve nut threaded upon the hollow stem for longitudinally moving the printing rollers, a collar threaded in the casing of the appa-
- ratus in which said sleeve nut is swiveled, 55 counter pressure rollers for coöoperating with the printing rollers, means operated by the rotation of the sleeve nut for longitudinally moving the counterpressure rollers simultaneously with the printing rollers, and 60 other connections from said threaded collar for similarly moving the counter pressure rollers.
9. In an apparatus of the character described, a rotatable shaft, a plurality of 65 stamp printing rollers mounted to rotate and move longitudinally on said shaft, means for rotatably connecting one or an adjacent pair of rollers to said shaft, an independent registering mechanism for each 70 printing roller, an independent shaft for operating each registering mechanism, and gearing operated from the main shaft adapted to drive gearing on each of the register shafts as the respective printing 75 rollers are brought into operative position.
10. In an apparatus of the character described, a rotatable shaft, a plurality of stamp printing rollers mounted to rotate and move longitudinally on said shaft, 80 means for rotatably connecting one or an adjacent pair of rollers to said shaft, counter pressure rollers for coöoperating with the printing rollers, a sliding shaft for longitudinally moving said counter pressure 85 rollers and a locking mechanism for alternately locking against rotation the rotatable shaft and the sliding shaft for moving the counter pressure rollers.
11. In an apparatus of the character described, a rotatable shaft, a plurality of 90 stamp printing rollers mounted to rotate and move longitudinally on said shaft, means for rotatably connecting one or an adjacent pair of rollers to said shaft, means 95 for moving said printing rollers longitudinally and advancing one or the other into stamping position and other means for moving said rollers longitudinally of the shaft for changing the position of impression of 100 the stamp on a letter.

In testimony whereof I have hereunto signed my name in the presence of two subscribing witnesses.

JULIUS LERCHE.

Witnesses:

HENRY HASPER,
WOLDEMAR HAUPT.
